ROOF

Donald F. Fradette, Cleveland, Ohio

Application February 17, 1937, Serial No. 126,181

3 Claims. (Cl. 108—17)

The invention relates to an improved roofing or roof covering, and more particularly relates to an ornamental breaker strip adapted to cover the adjacent paralleling edge portion of the shingle plates positioned below the breaker strip.

The object of the present invention is to provide an ornamental breaker strip, which not only acts as such, but also as a means to prevent snow and ice from sliding down the roof uninterruptedly in winter weather.

It is an object of the invention to provide a means to support a scaffold or support when making repairs upon the roof proper. The scaffold or support rests upon the breaker strips rather than upon the plates below the strips. Due to the fact that the breaker strip is thickest near its outer end tends to keep the support from slipping down over the roof when used thereon.

The accompanying drawing shows by way of example an embodiment of the present invention.

Figure 1 is a fragmentary plan view of a roof showing the breaker strip mounted thereon in accordance with the invention, a portion of a shingle element being broken away.

Figure 2 is an enlarged longitudinal side view of the breaker strip showing same in assembled relation.

Figure 3 is a view in perspective of the breaker strip without side flanges.

Figure 4 is a view in perspective of the breaker strip with side flanges.

Referring more particularly to the drawing, there is illustrated a commercial embodiment of the roof construction in Fig. 1, wherein the plates 10, 10 are each provided with slightly upturned flanges 11, 11 at their ends extending partly thereacross to provide a means for preventing rain and snow that might find its way under the breaker strip from reaching the conventional bituminous base material 24 placed below the shingle elements. The bituminous base material 24 is of a length equal to a plurality of spaced metal plates.

The breaker strip 12 is preferably shaped to the configuration and form as shown, and may be formed by a stamping operation by means of dies well known in the art.

In the construction shown in the drawing the breaker strip comprises a series of related planes having the geometrical form of triangles. The planes 13 and 14 are inclined to the point 15, which is also the high point in the breaker strip. The plane 16 inclines rearwardly and gradually flattens out into a plane 17 that coincides with

the plane of the shingle element below. The plane 18 inclines forwardly from the plane 16 and is provided with a hooked shaped portion 19 adapted to engage the underside of the base, the hooked flange 20 of the shingle elements being laterally notched as at 21, 21 to facilitate the reception of the hooked shaped portion 19 of the breaker strip.

The breaker strip may be provided with lateral side flanges 22 and 23, which act as bearings, and further act as stabilizing means against lateral deflection or distortion.

The vertically upward extending ends or flanges 11, 11 are covered by the breaker strip and the plates 10 may be laterally adjusted thereunder to favorably position them below the strip.

Since the operation and purpose of the breaker strip have been described in connection with the description thereof, it is believed that a résumé thereof is unnecessary.

The invention disclosed herein is obviously susceptible to various modifications and adaptations without departing from the scope and spirit thereof and it is not intended to limit the invention to the specific construction herein shown and described except as defined by the scope of the appended claims.

What is claimed is:

1. A roof structure consisting of a suitable asphaltum conventional water-proof base material of a length equal to a plurality of spaced metal plates, metal plates longitudinally spaced therealong, an upstanding flange on each end of each plate extending partly thereacross, a metallic breaker strip straddling the contiguous flanges on adjacent plates and having a top surface of a rib on the breaker strip maintained at a substantial elevation above the level of the plates whereby the velocity of snow and ice caused to travel by gravity is retarded in the direction of its movement.

2. A roof structure consisting of a suitable impervious asphalt base-material of a length equal to a plurality of spaced metal plates, metal plates longitudinally spaced therealong, an upstanding flange extending partly across each end of each plate, a breaker strip the aforesaid breaker strip bridging the joint between the plates and the confronting flanges together with a parallel portion of each plate adjacent said flanges, the breaker strip being so configurated that the partly flanged end of each plate may be slightly adjusted laterally thereunder, the breaker strip having a top surface of a rib on the butt end of

the breaker strip maintained at a substantial elevation above the plates so that the declination and speed of downwardly moving snow and ice is substantially retarded because of the said elevated rib.

5. 3. A roof structure consisting of a suitable impervious asphalt base-material of a length equal to a plurality of spaced metal plates, metal plates longitudinally spaced therealong, an upstanding flange extending partly across each end of each

plate, a metallic breaker strip straddling the upstanding flanges and having an off-set hooked end portion adapted to maintain the breaker strip against lifting movement from the plates, and having a top surface of a rib on the breaker strip maintained at a substantial elevation above the level of the plates whereby the velocity of snow and ice caused to travel by gravity is retarded in the direction of its movement.
